UNITED STATES PATENT OFFICE.

ALFRED KIELLAND, OF TRONDHJEM, NORWAY.

WINDING MACHINE FOR PIPE CONDUITS, ESPECIALLY WOODEN-STAVE PIPES.

1,402,515.

Specification of Letters Patent.

Patented Jan. 3, 1922.

Application filed October 10, 1919. Serial No. 329,843.

To all whom it may concern:

Be it known that I, ALFRED KIELLAND, a subject of the King of Norway, residing at Trondhjem, Norway, have invented certain new and useful Improvements in Winding Machines for Pipe Conduits, Especially Wooden-Stave Pipes, and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention has for its object a machine which is particularly adapted for the winding of wire about wooden stave pipes and the like in continuous operation and in any desired lengths. According to the present invention the wire winding apparatus is attached to a rotating ring-shaped disk arranged concentrically in relation to the pipe. In co-operation with the rotary movement of the ring-shaped disk the pipe has an axial movement, whereby the winding of the wire around said pipe may be properly placed.

Another object of this invention is to form a pipe forming machine or device of such a nature that it can be conveniently and permanently located in some well protected place and where there might be a limited amount of space available for the location of such a machine. The parts of this machine are few, more or less compact and easily and readily removable.

Another object of this invention is to provide such a device with feeding means which co-act or which may act separately to feed the pipe as it is being wound.

By a slight modification of the structure, but using the same general principles, a wire winding device might be formed in which the pipe is stationary, being surrounded by a casing that is longitudinally removable and which carries a rotating wire winding means for wrapping a wire around the pipe.

Other objects and advantages will appear from the following description taken in connection with the drawing, in which—

Fig. 1 is a side elevation of the winding

machine, showing a sectional view of the guide ring.

Fig. 1^a is an end view of the guide ring. 55

Fig. 2 is a view showing the main part of the machine seen in the longitudinal direction of the pipe.

As seen from Fig. 1 the whole device is mounted on the firm base of any suitable material and construction. At each end of the base is a track-way, upon which are mounted feeding and guiding carriages. Between the two feeding and guiding carriages are stands *b* and *h*, upon which the winding structure is located and through which a passage is provided for the pipe as it is being wound. Upon the stand *h* is arranged a gear wheel *g* concentric with the pipe and rotating around the pipe in the process of winding the wire. This gear wheel is rotated by means of a motor *i*, mounted upon a shaft *i* which carries a gear wheel meshing with the gear *g*. The motor used may be of any suitable and convenient kind, preferably in the present instance electric. Attached to one side of the gear wheel *g* is the winding drum *e* adapted to carry the wire by which the pipe is to be wound. For the purpose of drawing the wire tight around the pipe is provided a wire tightener *f* which is also mounted upon one side of the gear wheel *g*. Located on the base adjacent the wire winding means is a guiding ring *d* in which are mounted screw-adjusted rollers *m* serving as guiding and pressing rollers. These rollers guide the pipe as it passes through the stands and the gearing *g* and also serves to hold the staves in place while they are being wound. On one end of the base upon suitable runners or tracks is mounted a guide *c* having any suitable means for gripping the pipe *a*, which may be operated by handle wheel *n*. Attached to one end of this guide carriage *c* and extending for some distance therefrom is a rack bar *r* adapted to be engaged by a gear wheel *p*. On the other end of the base away from the carriage *c* is mounted a somewhat similar guiding carriage *l* to which is attached a similar rack bar *r*² adapted to be engaged by gear *p*² located on the opposite side of the device. 80 85 90 95 100

The carriages *c* and *l* have separately

located operating means. Each of these means consists of a speed-reducing gear mechanism mounted upon the ends of a transverse shaft s and having a common driving means, which is a gearing k meshing with the gear g . On each end of the shaft s is a bell-crank lever having an arm t . Upon this arm is a short shaft carrying a small gear p and a larger gear. This larger gear meshes with a small gear upon the shaft s , which carries integral with it a large gear, meshing with another small gear, supported by a shaft beneath the shaft s . This lower shaft also carries a larger gear meshing with a gear on the shaft carrying the aforementioned gearing k . It will be seen from the above description that by swinging the handle q of the bell-crank lever on the pivot point of the shaft s the pinion p may be removed from or brought in mesh with the rack r . The structure by which the rack r^2 attached to the guide carriage l may be engaged or disengaged by the pinion r^2 is similar to that just described, but located on the opposite end of the shaft s .

Having thus described my invention, what I claim and desire to secure by Letters Patent is:

1. In a winding machine for conduit pipes, a base, a stand mounted upon the base, a gearing mounted upon the stand, a wire drum mounted upon the gearing, means for actuating the gearing whereby the pipe is wound, and means movably mounted upon the base for feeding the pipe to the winding means.
2. In a winding machine for conduit pipes, a base, a stand mounted upon the base, a rotatable winding means mounted upon the stand, a wire drum mounted upon the winding means, a wire tightening means mounted upon the winding means, a pipe guide upon the base, and an adjustable pipe feeding means mounted upon the base for feeding the pipe to the pipe winding means.
3. In a winding machine for conduit pipes, a base, a stand mounted upon the base, a rotatable winding means mounted upon the stand, a pipe feeding means mounted upon the base, a second pipe feeding means mounted upon the base, and selective means for operating the pipe feeding means whereby the pipe may be fed to the winding means.
4. In a winding machine for conduit pipes, a base, a stand mounted upon the base, a rotatable winding means mounted upon the stand, a wire drum on the winding means, a pipe feeding means movably mounted upon the base, a second pipe feeding means movably mounted upon the base and selective means for operating the pipe feeding means whereby the pipe may be fed to the winding means.
5. In a winding machine for conduit pipes,

a base, a stand mounted upon the base, a winding means mounted upon the stand, pipe feeding means mounted upon the base, a second pipe feeding means movably mounted upon the base, a pipe guide mounted upon the base, and means for selectively operating the pipe feeding means, whereby the pipe may be fed to the winding means.

6. In a winding machine for conduit pipes, a base, a stand mounted upon the base, winding means mounted upon the stand, a wire drum mounted upon the winding means, a wire tightening means mounted upon the winding means, a trackway on the base, pipe feeding means mounted upon the trackway, and means for operating the pipe feeding means whereby a pipe is fed to the winding means.

7. In a winding machine for conduit pipes, a base, winding means mounted upon the base, a track upon the base, pipe feeding means mounted upon the track, a second trackway upon the base, a second feeding means mounted upon the last named trackway and selective means for operating the feeding means whereby a pipe may be fed to the winding means.

8. In a winding machine for conduit pipes, a base, a stand upon the base, winding means mounted upon the stand, a wire drum upon the winding means, wire tightening means upon the winding means, a pipe guide means upon the base, a trackway upon the base, pipe feeding means upon the trackway, a second trackway upon the base, a pipe feeding means upon the second-named trackway, means for operating the first feeding means, and means for operating the second feeding means.

9. In a winding machine for conduit pipes, a base, a winding means mounted upon the base, a trackway upon the base, a pipe feeding means mounted upon the trackway, a rack bar connected to the pipe feeding means, and a pinion engaging the rack bar whereby the pipe feeding means will be operated.

10. In a winding machine for conduit pipes, a base, winding means mounted upon the base, a trackway on the base, a pipe feeding means mounted upon the trackway, a rack bar connected to the pipe feeding means, a second trackway upon the base, a pipe feeding means mounted upon the second trackway, a rack bar connected to the last named pipe feeding means, and means for selectively engaging the rack bars whereby the pipe feeding means may be operated separately or in conjunction.

11. In a winding machine for conduit pipes, a base, winding means mounted upon the base, pipe feeding means movably mounted upon the base, a rack bar connected to the feeding means, a pinion engaging

the rack bar, a second feeding means mov- as my invention, I have signed my name in
ably mounted upon the base, a rack bar con- presence of two subscribing witnesses.
nected thereto, a second pinion engaging the
second rack bar, and selective means for
5 throwing the said pinions out of engage-
ment with their respective rack bars.

In testimony that I claim the foregoing

ALFRED KIELLAND.
